John F. Ryan INVENTOR

BY *Victor J. Evans*

Lynn Broton
WITNESS:

WITNESS:

ATTORNEY

UNITED STATES PATENT OFFICE.

JOHN F. RYAN, OF WOODBRIDGE, NEW JERSEY.

WALL CONSTRUCTION.

Application filed August 1, 1924. Serial No. 729,590.

To all whom it may concern:

Be it known that I, JOHN F. RYAN, a citizen of the United States of America, residing at Woodbridge, in the county of Middlesex and State of New Jersey, have invented new and useful Improvements in Wall Construction, of which the following is a specification.

This invention relates to improvements in wall construction and has particular reference to a building block or brick.

The principal object of the invention is the provision of a building block which is laid in horizontal rows one upon the other and after a number of rows have been laid, cement is poured in a manner to cause the same to enter pockets or cavities provided between the meeting faces of the blocks whereby to form an inside bond both horizontally and vertically of the wall, it being understood that the tendency of an outside bond is to collect moisture which penetrates to the inside of the wall surface.

Another object of the invention resides in a corner block which may be used as a right or left block, thus eliminating the necessity of constructing two different style blocks for corner construction.

Another object of the invention is to provide the building block of a composite texture in which the breaking strain both horizontally and perpendicularly is practically the same as that of a solid wall of building brick, and which will stand a pressure greater than a hollow tile wall now in use.

A further object is to construct a building block which may be employed for building a wall and which wall may be constructed by one unskilled in the art of building, as the blocks are provided with co-acting surfaces which serve to align them in proper vertical position.

A still further object is to provide a cement or brick building block which is simple in construction, cheap of manufacture and highly efficient for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of a portion of a wall constructed of my improved building blocks.

Figure 2 is a transverse vertical sectional view on the line 2—2 of Figure 1 and showing the cavities filled with cement.

Figure 3 is a perspective view of one of the runner blocks per se.

Figure 4 is a perspective view of one of the corner blocks per se.

Referring more particularly to the drawing, the reference numeral 10 designates my improved runner block in its entirety which consists of an oblong rectangular body 11, of concrete, brick or other suitable material having vertical side faces 12 which project slightly above the top and bottom faces to provide longitudinal flanges 13 for a purpose to be presently described. Formed in the underface of the body, and extending the length of the same centrally thereof is a groove 14, and arranged on the opposite face of the body centrally of the same is a tongue or rib 15. Disposed on opposite sides of the tongue and groove are longitudinal recesses 16 and 17 respectively. The body of the block is formed with rows of spaced vertical openings 18 which open into the recesses 16 and 17 on opposite sides of the tongue and groove. The end faces of the body are formed with vertical semi-circular recesses 19 which are in longitudinal alignment with the openings 18 whereby the meeting ends of a pair of blocks co-act to form a complete opening.

When laying the blocks for the construction of a wall as shown in Figures 1 and 2, the same are placed end to end in a horizontal row, after which the next row of

- blocks is applied by seating the tongues of the blocks of the first row in the grooves of the rows of the blocks in the next adjacent row, and when the tongue and grooves ⁵ are in co-acting position, the flanges 13 of the rows of blocks are in intimate contact with each other so that no space is left between the rows. The flanges 13 serve to support the blocks at the outer and inner ¹⁰ edges while the tongues support the weight or strain centrally thereof. In other words, the strain is evenly distributed throughout the length of the block. The horizontal rows of blocks are placed in staggered relation, that is, the blocks of one row overlap the meeting ends of the next adjacent row so that the wall structure appears similar to a wall constructed of the usual building blocks. ¹⁵
- After several rows of the blocks are placed in position, the openings in all the blocks are in vertical alignment to provide a continuous vertical passage, and the recesses 16 and 17 of the opposite blocks co-act to form horizontal cavities which communicate with the vertical openings. It will therefore be seen that mortar or cement may be poured in the ²⁰ respective openings to fill the cavities and openings whereby to form a bond between the horizontal rows of blocks, and a vertical bond between the meeting ends of the blocks. The operation is continued until the structure is complete. ²⁵
- It will be noted that the bonds are all concealed and no cement appears on opposite sides of the wall between the blocks which eliminates the trowel work usually required when laying blocks or bricks. Furthermore, the blocks may be laid by one unskilled in the art, as the blocks will automatically align themselves by reason of the tongue and groove construction. If desired, the vertical openings next to the outer side of the wall ³⁰ may be formed solid with cement while the inside openings can be poured alternately to leave certain of the openings unobstructed to permit of air circulation, or the passing of electric wires therethrough, or for suitable reinforcements. ³⁵
- In Figures 1 and 4, there is also shown a rectangular corner block or brick 10', which is identical with the construction of the runner block heretofore mentioned with the exception that the tongue 15' and the groove ⁴⁰ 14' extend only approximately half the length of the block, and an end flange 20 connects the longitudinal side flanges 13 on the opposite faces of the block. The recesses 16' and 17' on opposite sides of the tongue ⁴⁵ and groove respectively have communication with each other by reason of the length of the tongue. The corner block is also provided with vertical openings 18' and one end of the same is formed with semi-circular recesses 19' which co-act with the recesses 19 ⁵⁰ of one end of the next adjacent runner block to form vertical openings. It will be seen that the end flanges 20 rest upon the longitudinal flanges of the blocks above and below the same. The corner blocks are so constructed that they may be used either as a right or left block, thus making it unnecessary to construct two different style blocks for use at the corners of a wall. When set up for use, approximately one-half the ⁵⁵ length of each corner block overlies the end of the next adjacent corner block, which blocks are disposed at right angle to each other. ⁶⁰
- From the foregoing description, it will be seen that a wall may be easily and quickly constructed in which the cement for retaining the blocks in position is concealed on both sides, thereby giving the structure a neat and finished appearance. If desired, ⁶⁵ the inside of the face of the blocks may be formed with means for permitting the attachment of the furring strips but this would not interfere with the principal features of the block as any suitable means ⁷⁰ might be provided. ⁷⁵
- While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims. ⁸⁰ ⁸⁵ ⁹⁰ ⁹⁵ ¹⁰⁰
- What is claimed as new is:—
1. In a wall construction, a plurality of identical corner blocks disposed at right angle to each other, a seat provided on each of said blocks to receive an overlapping portion of the next adjacent block, runner blocks, and interlocking means between said corner blocks and said runner blocks. ¹⁰⁵
  2. In a wall construction, a plurality of identical corner blocks disposed at right angle to each other, a seat provided on each of said blocks to receive an overlapping portion of the next adjacent block, runner blocks engaging one end and one side of each corner block, interlocking elements between said corner blocks and said runner blocks, and cavities between all of said blocks for the reception of a cement for providing a bond between the blocks. ¹¹⁰ ¹¹⁵
  3. A corner building block for use as a right or left block comprising a rectangular body, and flanges extending from opposite faces of said body along three sides of the same and flush with the side walls thereof. ¹²⁰
  4. A corner building block for use as a right or left block comprising a rectangular body having openings extending therethrough, and flanges extending from opposite faces of said body along three sides of the same and flush with the side walls ¹²⁵ ¹³⁰

thereof, the remaining side wall being provided with vertical recesses.

5. A corner building block for use as a right or left block comprising an elongated body, flanges extending from opposite faces of said body along certain edges thereof, a tongue extending from one face of said body centrally thereof and terminating short of one end thereof, and a groove in the opposite face of said body of a length equal to the length of said tongue.

In testimony whereof I have affixed my signature.

JOHN F. RYAN.
